UNITED STATES PATENT OFFICE

WILFRID GAY, OF CONCORDIA, KANSAS

IRONING BOARD

Application filed August 10, 1931. Serial No. 556,281.

This invention relates to ironing boards of the type adapted to be folded or collapsed against a wall or other upstanding structure.

One of the objects is to provide a device of this character utilizing foldable supporting means controlled by springs which act to bring said means into position to support the board positively in its folded or raised position.

Another object is to provide as a single article of manufacture an attaching frame to which the board is connected and in which it is adapted to be housed when not in use.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is a front elevation of the ironing board in its raised or folded position.

Figure 2 is a section on line 2-2, Figure 1, the board being shown by broken lines in partly lowered position.

Figure 3 is an enlarged section on line 3-3, Figure 1.

Figure 4 is a side elevation showing the ironing board lowered to position for use, its housing frame being in section.

Referring to the figures by characters of reference, 1 designates a flat frame having an opening 2 of such shape and size as to allow an ironing board to fit snugly therein. This frame is to be attached to a wall W or the like by screws or other suitable fastenings 3.

The ironing board has been indicated at 4 and its lower end is connected to the lower portion of frame 1 by hinges 5 having springs 6 which are sufficiently strong to maintain the board within recess 2 after it has been moved upwardly a predetermined distance. When the board is thus located it will practically fill recess 2 and by providing the board

with a flange 7 along the sides and free end thereof the frame can be lapped by the flanges and the recess 2 thus completely concealed.

A fabric cover 8 is provided for the board and the edge portions thereof are held tightly to the board by a wire band 9 or the like, as shown.

A bracket is attached to the outer side of the board 4 as shown at 10 and pivotally attached to the bracket is a leg 11 the lower end portion of which is forked and joined by a link 12 to another bracket 13 secured to the structure W below the frame 1. A longitudinal groove 14 is formed in the upper end portion of leg 11 and secured in the lower end of this groove is a tension spring 15 the upper end of which is attached at 16 to board 4. A handle 17 is attached to the leg 11 as shown.

When the board 4 is not in use it is seated in recess 2 where it is retained by the springs 6 of hinges 5. At the same time the leg 11 is drawn tightly against the outer surface of the board by spring 15 so that the leg and its link 12 will be held in alignment and provide a further support for the closed board. The board 4 can be lowered readily at any time by pulling on handle 17. This will cause the leg 11 and link 12 to move to the positions shown in Figure 4, the weight of the parts being sufficient to overcome the action of all of the springs when the board is lowered.

To raise or fold the board it is necessary merely to exert a light lifting pressure and this, with the aid of all of the springs, will bring the board to its position in frame 1. Any attempt to lower the board except by pulling on handle 17 will fail because the leg 11 and link 12 will shift toward the wall W as shown by broken lines in Figure 2 and stop the movement of the board. Thus there is no danger of the board falling accidentally.

What is claimed is:

1. The combination with a recessed frame for attachment to a wall or the like, of an ironing board hingedly connected at one end to the frame, a spring for holding the board yieldingly in an upstanding position in the recess, a leg hingedly connected to the board, a link hingedly connected to the leg, means for hingedly connecting the link to a wall or the

like, said leg constituting means for supporting the board in operative position, and a tension spring connecting the leg and board for holding the leg and link normally in alignment while the board is seated in the recess.

2. The combination with a recessed frame for attachment to a wall or the like, of an ironing board hingedly connected at one end to the frame, a spring for holding the board yieldingly in an upstanding position in the recess, a leg hingedly connected to the board, a link hingedly connected to the leg, means for hingedly connecting the link to a wall or the like, said leg constituting means for supporting the board in operative position, a tension spring connecting the leg and board for holding the leg and link normally in alignment while the board is seated in the recess, there being a groove in the leg for housing said spring when the leg and link are in alignment, said spring constituting means for shifting the leg and link backwardly against the wall and under the frame when the board is moved outwardly from the recess and against the leg, thereby to limit said movement and prevent the board from falling.

In testimony that I claim the foregoing as my own, I have hereto affixed my signature.

WILFRID GAY.
